PRESS FOR PRODUCING FLOUR PASTE
ARTICLES

Emil Giezendanner, Oberuzwil, Switzerland, assignor to the firm Buhler Brothers, Uzwil, Switzerland

Application May 12, 1939, Serial No. 273,354
In Germany April 1, 1939

3 Claims. (Cl. 107—14)

This invention relates to regulating devices for presses for producing flour paste articles.

It is known to provide presses for producing flour paste articles, particularly vermicelli, with a dispensing tube and to insert therein a number of cylindrical sizing members. The slender strands of vermicelli are formed by pressing the material through these sizing members in the form of separate bundles of strands which bundles, as a rule, align in order to be formed into bunches by so-called bunching machines.

The present invention is particularly concerned with regulating devices for presses for producing flour paste articles which devices, however, do not discharge individual bundles but individual strands of flour paste, which are preferably in the form of macaroni or spaghetti.

According to the invention, the strands discharging from sizing members connected to a dispensing tube are united into groups, the velocity of discharging of the strands being regulatable for each group separately.

With this arrangement it is possible to deposit the strands on the bars of a grating in such manner that the bars are hung with strands uniformly throughout the grating. The flour paste articles are then dried in a known manner.

It is, however, necessary that the flour paste strands hanging on the bars shall be practically of a uniform length. In the usual forms of dispensing devices the velocities at which different strands discharge are, however, not exactly alike. Thus, when it is required to obtain strands of uniform lengths resort must be taken to cutting the strands after they have been placed on the bars, whereby undesirable waste accrues. This drawback is eliminated by the invention, in that the velocity of discharge of the individual groups of strands is regulatable.

Advantageously, for each group of strands a cylindrical sizing member is provided from which the strands discharge longitudinally of a generatrix of the cylinder and which is arranged within a head connected to the dispensing tube. The heads can be detached from the dispensing tube very quickly in simple manner by virtue of which the interchanging of sizing heads requires the operation of the press to be discontinued only for a very short time providing two sets of such heads are employed.

An embodiment of the invention is illustrated on the accompanying drawing by way of example only, in which

Fig. 1 shows a side elevation of a dispensing

device, according to the invention, partly in longitudinal section;

Fig. 2 is a bottom view of Fig. 1;

Fig. 3 is a cross section of Fig. 1, and

Fig. 4 is a horizontal section on the line IV—IV of Fig. 3.

The dispensing device shown is provided with a dispensing tube 1 to which are connected a plurality of heads 2 within each of which a sizing member 3 provided with a plurality of discharge openings is arranged. The dispensing tube 1 is electrically heated along its full length by means of subdivided heating elements 4 which are pressed onto the flat surfaces 1a of the dispensing tube by plates 5, in such manner, that even if only groups of heating elements are connected with the heating current the dispensing tube is heated uniformly throughout its length. A sheet metal shell serves as a heat insulating and guard member against the accidental touching of current carrying parts. Control screws 1 are screwed in dispensing passages 1b of the dispensing tube 1 and are secured in position by lock nuts 8 in such manner that the streaming area of the passage and thus the stream of paste passing therethrough can be varied by the passage being throttled more or less. By this means the non-uniform feed to the individual heads 2 resulting from a drop in pressure in the dispensing tube 1 can be equalized, so that the velocity of discharging of the flour paste strands from the sizing members 3 can be adjusted to a uniform value also.

The upper cylindrical neck of the head 2 is connected to the dispensing tube 1 by a screw 35 sleeve 9 through the intermediary of a sleeve 11. The sleeve 11 is rotatable relative to the screw sleeve 9 when the latter is loosened. The sleeve is, however, secured against axial displacement by an annular spring clamp 10 and is provided with two diametrically opposed longitudinal grooves 11a. The cylindrical neck of the head 2 is provided with two studs 2a corresponding to these grooves so that the neck can be detached or reinserted in position when the sleeve 11 has been turned through 90° from its position shown in Fig. 4. On the insertion of the neck of the head 2 in the sleeve 11 the latter is turned through 90° again into the position shown in Fig. 4, whereupon the screw sleeve 9 is tightened and consequently the head 2 is secured to the dispensing tube 1 in readily detachable manner.

The cylindrical sizing member 3 which is provided with sizing apertures for individual paste strands along a generatrix of this member is 55

inserted in a bore 2b of the head 2 and fixed in position against axial displacement by two screws 12. The sizing member 3 is further secured against rotational displacement by a screw 13. A 5 guide rib 2c arranged in the head 2 serves for uniformly distributing the paste.

Various changes and modifications may be made in the constructional details without departing from the ambit of the invention, by adding customary practice and established knowledge of the art to the present disclosure while the scope of the specification and claims is not to be regarded as limited except as specified therein.

15 15 I claim:

1. In a dough press for forming strands of dough, means forming a common feed channel, a plurality of hollow head members, the form of said head members being such that the cavities 20 thereof taper toward said channel, means forming individual connecting passages between said channel and the smaller ends of said cavities, cylinders having sizing openings serving as molds for the dough strands to be formed in said hollow members, and individually adjustable means 25 adapted to extend into said passages between said channel and said sizing openings for regulating the cross-section of said respective passages to regulate the flow of dough to said respective molds.
2. In a dough press for forming strands of dough, means forming a common feed channel, a plurality of hollow head members, the form of

said head members being such that the cavities thereof taper toward said channel and the end opposite the channel is elongated in one direction, said members each being provided with an elongated slot at the elongated end thereof, 5 means forming individual connecting passages between said channel and the smaller ends of said cavities, cylinders having sizing openings lying in a line and serving as molds for the dough strands to be formed in said hollow members, 10 and individually adjustable means adapted to extend into said passages between said channel and said sizing openings for regulating the cross section of said respective passages to regulate the flow of dough to said respective molds.

3. In a dough press for forming strands of dough, means forming a common feed channel, a plurality of hollow head members, the form of said head members being such that the cavities thereof taper toward said channel, means forming individual connecting passages between said channel and the smaller ends of said cavities, said connecting means being detachable from said channel forming means, cylinders having sizing openings lying in a line and serving as molds 25 for the dough strands to be formed in said hollow members, and individually adjustable means adapted to extend into said passages between said channel and said sizing openings for regulating the cross section of said respective passages to regulate the flow of dough to said respective molds.

EMIL GIEZENDANNER.
